TRAVELING CASE

David Reismann, Bratislava, Czechoslovakia

Application December 17, 1934, Serial No. 757,798
In Czechoslovakia January 12, 1934

10 Claims. (Cl. 190—41)

This invention relates to trunks and suit-cases of the portable-wardrobe type, and has for its object to increase the efficiency and convenience in use of articles of this nature.

5 It is already known to provide suit-cases with a self-contained wardrobe fitting consisting of two inter-articulated frame-like portions which are housed within the case when the latter is closed, and which can be opened out and erected 10 to form a wardrobe rack when the case is open.

The present invention relates to trunks and suit-cases equipped in this manner, and comprises particular features of the construction both of the trunk or suit-case itself and also of 15 the collapsible wardrobe fitting contained therein. In accordance with the invention, the bottom or body portion of the trunk or suit-case, in which the collapsed wardrobe fitting is housed, is made with rigid walls and connected 20 along one edge to the top or lid portion which has rigid side walls for a part of its depth and is collapsible and expandable for the remainder of its depth. Further, the portion of the collapsible 25 wardrobe fitting which lies uppermost in the collapsed condition is provided with an auxiliary frame which is capable of being extended into the additional space obtained by the expansion of the lid portion, thus enabling a larger number of garments to be coped with.

30 A form of construction embodying the invention is shown by way of example in the accompanying drawings, in which:—

Fig. 1 shows a suit-case in accordance with the invention, in the open condition, with the 35 wardrobe fitting folded out and erected.

Fig. 2 is a transverse section of the open suit-case with the wardrobe fitting in the collapsed condition.

40 Fig. 3 shows the lid distended.

Figs. 4 and 5 show the construction of the device for the suspension of the clothes hangers.

Fig. 6 shows a clothes hanger for use with the present invention.

45 Figs. 7 and 8 illustrate the manner in which the two parts of the wardrobe fitting are connected together.

The trunk or suit-case according to the invention consists of a rigid-walled bottom or body portion 1 with compartments for different classes 50 of articles and adapted to accommodate the wardrobe fitting in the collapsed condition. The partition 2 serves as a support for the wardrobe fitting and is of such height that the latter is held approximately parallel to the bottom 55 of the trunk or suit-case. The wardrobe fitting

itself consists essentially of the frame portions 3, 4. To the lower part 3 there are articulated props 5 the free ends of which engage by means of studs 6 in guide slots 7 provided with end detents 8, 9 for determining the end positions 5 of the props 5 and therefore also of the wardrobe fitting as a whole. The part 3 is pivoted to the body portion 1 of the trunk or suit case by means of hinges 10, and is articulated by means of hinges 11 to the upper part 4 of the 10 wardrobe fitting. Along the joint between the parts 3 and 4, and covering the hinges 11, there is provided a roll 12 preferably of fairly stiff leather which prevents the clothes from becoming sharply creased when the wardrobe fitting 15 is collapsed and the trunk or suit-case closed and fastened down. On the part 4 there are provided parallel clasps 13, 14 which grip the side members of the part 3 when the fitting is extended, the clasps being provided with a 20 recess adapted to engage a stud 15 on the part 3 and thereby to determine the relative positioning of the parts 3 and 4. The part 4 is equipped with an auxiliary frame 16 which serves to increase, when required, the space enclosed by the part 4 of the wardrobe fitting. 25 This auxiliary frame 16 is provided with slots 17 which coact with the guide studs 18 to allow this frame to be slid parallel to the part 4.

The part 4 is further provided with a suspension device for the reception of the lateral hooks 19 of the clothes hangers 20 (Fig. 6). The suspension device consists of tubular members 21 which are secured to the part 4 of the wardrobe fitting at 22, and which are recessed as at 23 35 (Fig. 5). Within the tubular members 21 there are provided telescoping extension rails 24 provided with a stop 25 which moves within the recess 23 and determines the limiting positions of the extension rail. The length of the rails 24 and of the recesses 23 is such that the enlarged head end 26 of the rails 24 project, with the latter 40 in the extended condition, beyond the forward edge of the auxiliary frame 16, when the latter is in its operative position, so that there is sufficient clearance at the ends of the rails to admit of the insertion and removal of the clothes hangers one by one, with the end hooks 19 in engagement with the rails 24.

45 The top or lid portion of the trunk or suit-case 50 consists of a rigid portion 27 adjoining which there is an extensible bellows portion 28 to which the top sheet or plate 29 is attached. The extensible bellows portion 28 can be retained in the collapsed condition by means of straps 30. When 55

it is desired to increase the holding capacity of the trunk or suit-case to the extent permitted by the utilization of the auxiliary frame 16 the straps 30 are first slackened off, and the bellows portion 28 then stretched and retained in the extended condition by means of braces 31 which are pivoted about pins 32 on the part 27 (Fig. 3). The space enclosed by the top portion of the trunk or suit-case can thus be augmented to correspond to the increase in holding capacity effected by the use of the auxiliary frame 16, and there will be no danger of the top plate 29 pressing too hard on the clothes in the trunk or suit-case.

The part 3 of the wardrobe fitment is preferably provided with a two-part curtain 33 which is strengthened by inlaid straps 34 and adapted to be closed by means of snap buttons 35 or the like. This curtain tends to hold fast the lower portion of the clothes suspended from the hangers 20, with the result that a stretching action is exerted upon the clothes when the wardrobe fitment is folded down into the collapsed position. In this manner any creases present in the clothes tend to be eliminated, and the clothes will be found to be free from creases when taken out of the trunk or suit-case according to the invention, even after having been stowed away therein for a considerable length of time without interruption.

30. What I claim is:

1. A traveling case comprising in combination a rigid-walled bottom section, a partly rigid-walled and partly expandible lid section hinged to the said bottom section, a collapsible wardrobe fitment consisting of two articulately interconnected frame parts pivotally mounted by the lower of the said parts to the said bottom section and adapted when folded back on each other to form a composite frame which fits within the contour of the said bottom section, and an auxiliary telescoping frame associated with the upper of the said parts and adapted to project into the extra lid space obtained by the expansion of the said expandible part of the lid section of the case.

2. A traveling case comprising in combination a rigid-walled bottom section, at least one transverse partition in the said bottom section of a height less than the depth of said bottom section, a partly rigid-walled and partly expandible lid section hinged to the said bottom section, a collapsible wardrobe fitment consisting of two articulately interconnected frame parts pivotally mounted by the lower of the said parts to the said bottom section and adapted when folded back on each other to form a composite frame which fits within the contour of the said bottom section and rests upon the said partition, the said partition being of such height that the said wardrobe fitment when collapsed lies substantially parallel to the bottom of the case, and an auxiliary telescoping frame associated with the upper of the said parts and adapted to project into the extra lid space obtained by the expansion of the said expandible part of the lid section of the case.

3. A traveling case as claimed in claim 1 in which the said auxiliary frame is slidable on the said upper part by means of slot guides.

4. A traveling case comprising in combination a rigid-walled bottom section, a lid section hinged to the said bottom section and consisting of rigid side walls, a top plate, and an expandible bellows section between the said side walls and top plate, a collapsible wardrobe fitment consisting of two articulately interconnected frame parts pivotally

mounted by the lower of the said parts to the said bottom section and adapted when folded back on each other to form a composite frame which fits within the contour of the said bottom section, and an auxiliary telescoping frame associated with the upper of the said parts and adapted to project into the extra lid space obtained by the expansion of the said bellows section. 5

5. A traveling case as claimed in claim 4, further comprising braces pivoted to the inside of the said side walls for the purpose of stretching and retaining the said bellows section in the expanded condition. 10

6. A traveling case comprising in combination a rigid-walled bottom section, a partly rigid-walled and partly expandible lid section hinged to the said bottom section, a collapsible wardrobe fitment consisting of two articulately interconnected frame parts pivotally mounted by the lower of the said parts to the said bottom section and adapted when folded back on each other to form a composite frame which fits within the contour of the said bottom section, slotted guides attached to the inside of the said bottom section, props pivoted to the lower of the said frame parts and adapted to engage with their free ends in the said slot guides, arresting detents on the said guides adapted to retain the said props alternatively in a position corresponding to the erected condition of the said wardrobe fitment 20 and in a position corresponding to the collapsed condition of the said fitment, and an auxiliary telescoping frame associated with the upper of the said parts and adapted to project into the extra lid space obtained by the expansion of the 25 said expandible part of the lid section of the case. 30

7. A traveling case as claimed in claim 1 further comprising pairs of clasp members attached to the upper of the said frame parts and adapted, on the folding out and erecting of the 40 said wardrobe fitment, to come into gripping engagement with the side members of the lower of the said parts, for the purpose of preventing unintentional collapsing of the said fitment.

8. A traveling case as claimed in claim 1 further comprising a roll of flexible material disposed along the joint between the said frame parts and attached to the said parts on the side of the said fitment furthest removed from the lid section of the case when the said fitment is 50 in the erected condition, for the purpose of preventing creasing of the clothes on the collapsing of the said fitment. 45

9. A traveling case comprising in combination a rigid-walled bottom section, a partly rigid-walled and partly expandible lid section hinged to the said bottom section, a collapsible wardrobe fitment consisting of two articulately interconnected frame parts pivotally mounted by the lower of the said parts to the said bottom section and adapted when folded back on each other to form a composite frame which fits within the contour of the said bottom section, an auxiliary telescoping frame slideable in slot guides on the upper of the said parts and adapted to project 60 into the extra lid space obtained by the expansion of the said expandible part of the lid section of the case, recessed tubular holders attached to the inside and near the top of the side members of the upper of the said frame parts, extension rails for the suspension of clothes hangers telescoped within the said tubular holders and adapted to project outwards beyond the forward edge 65 of the said auxiliary frame in the position of use, 70 75

and a stop on the said rails adapted to engage in the recessed portion of the said holders.

5 10. A traveling case as claimed in claim 1 further comprising a reinforced curtain associated with the lower of the said frame parts and adapted to be laid with tension across the lower

portion of the clothes stowed within the said wardrobe fitment, for the purpose of holding the said clothes fast and causing the same to become stretched by the act of collapsing the wardrobe fitment into the case.

5

DAVID REISMANN.
